RAILWAY TRACK ALIGNER

Bernard Geier, Moscow, Pa., and John P. Hiltz, Jr., Scarsdale, N.Y., assignors to Railway Track Works Company, Philadelphia, Pa., a corporation of Pennsylvania

Application August 31, 1953, Serial No. 377,272

2 Claims. (Cl. 254—43)

Our invention relates to a method and apparatus for aligning railway track.

An object of our invention is to align track in a minimum of time, effort and expense.

An object of our invention is to make such alignment possible without the aid of the large number of workmen now normally employed to perform it.

Other objects and advantages will be apparent from the further description and the claims.

Figure 1 of the drawings, which show an embodiment of our invention, is a perspective view of our track aligning device in actual operation upon a piece of track, fragmentarily shown.

Figure 2 is a view in elevation of the jacking portion of our device resting with its spade flat, out of use.

Figure 3 is a view of that same portion in longitudinal section thru the middle, but broken away at the bottom near the tip of the spade; in this case it is shown in position of use, along with a fragmentary showing of the track.

Figure 4 shows a plan view of the spade which forms part of the jacking portion of the device, sectioned thru the bar which connects it to the body of the jacking portion in the middle, and including the associated bolt and nut at the rear, but not any of the associated body tail-piece there.

Figure 5 shows a fragmentary end view of the body of this portion of the device, looking from the head end along the line of the axis of the cylinder.

Figure 6 shows a plan view of the frame-work of the movable carriage portion of the device.

Figure 7 shows a view of the above in elevation on a rail fragmentarily shown.

Figure 8 is a fragmentary view of the above, sectioned along the line 8—8 in Figure 6.

Turning to the description of this embodiment of the device of our invention, it includes one or more jacking portions 10 and a carriage portion 12, together with hose lines 14 for pressure fluid running from one to the other.

The jacking portion is made up of a body 16 and a spade 18, positioned at an acute angle with each other with the apex more or less at their rear end, and joined together not only at their rear end, but also by a bar 20 part way along. The body, which in operation is placed in horizontal position with head against the rail (see Figure 3), has a ram 22 whose tapered head 24 in such case will abut the web 25 of the rail. Piston 28 on the rear end of the ram operates in cylinder 30 under the influence of pressure fluid admitted at either end from the hose through openings 32 and 34 in the cylinder wall. The cylinder is reinforced by jacket 36 to the top of which is attached handle 38, and at the bottom toward the head end of which is welded the previously-mentioned bar 20.

Spade 18 is mostly in the shape of an inverted channel bar, having a cross section in the shape of an inverted U, with broad flat portion 40 on top, and side walls 42 extending down. But at the front end 44 the broad flat

2

portion slopes down at an angle toward the bottom of the side walls, and the side walls are prolonged in the form of a corresponding triangle to meet it, so that the tip end as a whole might be said to form a sort of hollow bevel.

The front tip 46 of this sloping part or "bevel" is preferably made of an especially hard steel, which may, for example, be applied by welding, and the very tip 48 is preferably somewhat rounded rather than absolutely sharp.

At the rear end of the spade, the attachment to the rear end of the body can take any suitable form; in the example shown it is done by having a clevis arrangement 50, consisting of two separated sleeves 52, affixed on the top of the spade, and tail piece 56 on the rear of the cylinder positioned between the sleeves of the clevis, with bolt (and associated nut) 58 pinning clevis and tail piece together. The top part of the channel may be cut away in the center rear to permit the tail piece to come between the arms of the clevis, if necessary. Extending out to the rear from the clevis is handle 60. Welded on, more or less midway along the top of the channel is reinforcing piece 61, to which bar 20 is welded.

In the device of our invention, the particular angles and dimensions used can be highly important. In a specific form which will work, and is our preferred form, the body is about 19 inches long tip to tip in its contracted position, with a 10 inch stroke making it about 29 inches long in its extended position. The spade is about 19 inches long which makes a distance of somewhat over 21 inches from the very tip along a line at the very bottom of the sides of the channel to the point where the prolongation of this line meets the prolongation of the body center line. The angle between body and spade is 40°. In cross section, the channel forming most of the spade is 7 inches across from edge to edge and 2 inches deep from its top to the bottom of the sides. The "bevel" forming the end of the spade is about 42° in angle with relation to the projected direction of the top of the channel.

In other specific forms which have been tried and have worked, a spade about 21 inches long has been used, with around 23 inches from its tip to the point where the prolongations of the earlier mentioned lines would meet and with angles between body and spade of 45° in one case and 50° in another.

In general, the angle between spade and body should preferably be from about 40° to about 50°, with about 40° the most to be preferred, the distance along the bottom line of the channel from the tip to the point where the prolongation of that line meets the prolongation of the body's center line should preferably be around 22 inches, the cross-sectional width of the channel should preferably be about 7 inches, the depth of the channel should preferably be at least about 2 inches and the angle which the "bevel" at the end of the spade makes with the prolongation of the top of the channel should preferably be from about 40° to about 45°.

The pressure for the piston is supplied by use of pump 64 driven by gasoline motor 66, and operated in conjunction with storage tank 68 for hydraulic fluid, all located on carriage portion 12. The pump, motor and tank can take any suitable standard form adequate to develop the pressure needed, and are therefore shown merely diagrammatically. It has been found for example that a commercial 3 to 5 horsepower gasoline motor pump which at 1500 r.p.m. would develop 3000 pounds per square inch is entirely suitable when the jacking portion of our device has a piston of adequate area. A piston area which would, for example, produce 10 tons

of actual force in the forward stroke at the pressure used is entirely adequate.

The pressure fluid can be of any suitable kind, such as, for example, hydraulic oil. It passes through suitable control valves (not shown), well known in the art, controlled from control panel 70, which can cut the pressure connection off altogether or can direct the pressure fluid through the appropriate line of hose 14 to cylinder opening 34 or 32, depending on whether a forward stroke or a retraction of the ram is desired, with pressure fluid at the same time going out of the other cylinder opening to the tank. Pressure gage 71 is located at cylinder opening 34 on one of the jacking portions.

In carriage portion 12, flanged track wheels 72 support main platform 74, which in turn supports pump mount 75 for pump 64, motor mount extension 76 for motor 66, hydraulic control mount extension 78 for hydraulic control board 70, and tank bracket 80 for tank 68. Handles 82 extend from each of the corners. Carriage foot 84 is mounted on the edge of the hydraulic control mount extension 78 by means of hinge lug members 86 and pins 88 about which it swings. Its sides 90 joined together by bottom 92 are angle irons with one angle extending down parallel to the outside edge of the control mount extension, so that the inside of this angle stops the foot from swinging beyond vertical downward position, while the location of the end of the angle iron at a point even with the top of the control mount extension when the foot is in vertical position stops the foot from swinging beyond vertical upward position. Tension spring 94, stretching from an intermediate point on the outside of the leg to an intermediate point on the outside of the transverse edge 96 of the hydraulic control mount extension, urges the foot toward which ever end of its swing is nearest. The carriage portion and its various components are so arranged that the center of gravity of the whole thing will be in the direction of the foot from the center of the portion of the wheel intended to bear on the rail, to a degree sufficient so that in normal standing position part of the weight will be on the foot, although not sufficiently to seriously unbalance the carriage in traveling.

In operation, when the track is out of alignment and needs to be moved over a bit, enough of the ballast between the ties at that point is dug out to enable the sloping spade of the jacking portion of our device to be pushed down to a point where, with the under side of the spade resting on ballast, the body of the jacking portion, with its ram retracted, is in horizontal position with its head resting against the inner side of the web of the rail. Care should be taken that the body is not appreciably sloping in either direction.

Once the jacking portion is in position, pressure is applied gradually at the very outset and then strongly after the spade has gone back a little and seated itself, which normally requires perhaps a couple of inches. By this means, the track, ties and all, will be pushed in the direction of travel of the ram for a distance which will be on the general order of 5 inches if the entire stroke is utilized. Additional jacking portions can be used if desired, as shown in Figure 1.

When we consider that such a large force is being employed against the rail by a horizontally directed ram with the entire support for this action coming from such a loose material as ballast located near by and so much lower down, it may seem surprising that the device of our invention is effective to do the job, but it is highly so.

With the aid of this device, track which is out of alignment to either side can readily be straightened without requiring the aid of the large gang of workmen, normally about fourteen, which is now ordinarily employed for this purpose. Instead, it can be done by a much smaller group, five being highly suitable, with consequent great reduction of costs.

When an operation at one location is complete, the jacking portion can be picked up and if need be the carriage portion can be moved along the rail on its wheels or carried by the handles. In moving on its wheels, the carriage portion can be tilted to bring its foot out of possible contact with the ties, or if desired the foot can be kicked up, from its stationary position extending downward to the ground, to its upward extending position.

In view of our invention and disclosure variations and modifications to meet individual whim or particular need will doubtless become evident to others skilled in the art, to obtain all or part of the benefits of our invention without copying the structure shown, and we, therefore, claim all such insofar as they fall within the reasonable spirit and scope of our claims.

Having thus described our invention what we claim as new and desire to secure by Letters Patent is:

1. A track aligning device comprising a horizontally directed cylinder adapted to receive fluid pressure, a source of fluid under pressure connected to said cylinder, a horizontally directed ram having at one end a piston operating in said cylinder and at the other end a head adapted to contact the side of a rail, the direction toward said head being hereinafter denominated "forward," a foot attached to the rear end of the cylinder and extending slopingly downward in a forward direction therefrom at an angle of about 40 degrees, to a point nearly under, but short of, the forward end of the cylinder, said foot having a flat top member extending nearly all its length, two side members extending its entire length, and an end member at the forward end thereof and slightly forwardly from the forward end of the top member to the bottom of the forward ends of the side members, and a stiff member rigidly connecting a point in the mid-third of the top member of the foot to a point in the forward third of the cylinder.
2. A track aligning device of claim 1, in which the distance along the longitudinal center line of a portion of a plane bounded by the edges of the side members, the edge of the end member, and a line connecting the ends of the edges of the side members remote from the end member, is 22 inches.
